US0D1017714S

(12) **United States Design Patent** (10) Patent No.: **US D1,017,714 S**
(45) Date of Patent: ** Mar. 12, 2024

(54) **ROCKER**

(71) Applicant: **Williams-Sonoma, Inc.**, San Francisco, CA (US)

(72) Inventor: **Jocelyn Yao**, San Francisco, CA (US)

(73) Assignee: **Williams-Sonoma, Inc.**, San Francisco, CA (US)

(**) Term: **15 Years**

(21) Appl. No.: **29/822,151**

(22) Filed: **Jan. 6, 2022**

(51) LOC (14) Cl. **21-01**

(52) U.S. Cl.

USPC **D21/412; D21/414; D21/417; D21/533; D21/540**

(58) **Field of Classification Search**

USPC D21/398, 412, 414, 417, 419, 533, 539, D21/540

(57) **CLAIM**

The ornamental design for a rocker, as shown and described.

DESCRIPTION

FIG. 1 is a perspective view of the rocker;

FIG. 2 is a front elevational view of the rocker;

FIG. 3 is a rear elevational view of the rocker;

FIG. 4 is a left side elevational view of the rocker;

FIG. 5 is a right side elevational view of the rocker;

FIG. 6 is a top plan view of the rocker; and,

FIG. 7 is a bottom plan view of the rocker.

The broken lines shown in the drawings are included to show portions of the rocker that form no part of the claimed design.

1 Claim, 7 Drawing Sheets
